ACCOUNTING MACHINE

Alvin E. Gray, Flushing, N. Y., assignor, by mesne assignments, to International Business Machines Corporation, New York, N. Y., a corporation of New York

Application June 18, 1931, Serial No. 545,256

15 Claims. (Cl. 235—61.8)

This invention relates to improvements in accumulating and total printing devices, and more particularly to improved electrical devices for controlling the printing of a negative balance under control of a duplex accumulator. The illustrative machine performs accounting operations under control of perforated record cards.

The devices used in illustrating the present invention are similar in many respects to the accumulating and totaling devices shown in the application of J. R. Peirce, Serial No. 534,583, filed May 2, 1931. Briefly, the outstanding differences between the devices in the present application and the devices of the Peirce application are: the re-arrangement of total circuit closing contacts in the accumulator, the elimination of "elusive one" carrying means, and the addition of a set of zeroizing contact devices which is timed to correct negative balance printing. In order to clearly and definitely point out the improvements of the present invention, there follows; first, a brief description of the devices as they appear and operate according to the Peirce disclosure; and then, a description of the re-arrangements in, and additions to, the Peirce devices according to the present invention with resulting improvement in mode of operation.

The Peirce application discloses two sets of accumulating wheels connected by gearing so that they revolve in opposite directions. The one set of accumulator wheels is normally positioned at zero and serves to add credit items and subtract debit items, while the other set of accumulator wheels is normally positioned at nine and is adapted to subtract credit items and add debit items. Because of the gear connections between the two sets of wheels, the operation of the one set in adding an amount causes the subtraction of the same amount from the other set. A balance in the accumulator unit is manifested as a true number in one set of accumulator wheels and as a complement in the other set of wheels. A number added to an amount in one accumulator is subtracted from the complement of said amount in the other accumulator. An "elusive one" carrying means is provided between the highest and lowest order wheels of both accumulators. When a set of wheels containing a complement has added thereto an amount sufficient to cause the set to register a true number (i. e., for the highest order wheel to go from nine to zero) the "elusive one" carrying means transfers a unit to the lowest order wheel, thus filling in the amount to show a balance as a true number on said set of wheels, and as a nines com-

plement on the other set of accumulator wheels. After the entry of items it is often desirable to print a record of the balance. For this purpose each of the accumulator wheels is provided with a totaling cam for operating total contacts which when closed complete a circuit through the printer. The sets of accumulator wheels have separate sets of total contacts. The total contacts in the credit accumulator are closed when the accumulator wheels stand in normal position (i. e., at zero). The total contacts in the debit accumulator are normally opened (i. e., with the wheels at nine) and are closed when the wheels are in the zero position. Early in a totaling operation, a circuit containing the total contacts associated with the highest order wheel in the debit accumulator is made effective to sense the condition of the contacts. Should the wheel stand at zero, the contacts are closed indicating that a negative balance is present as a true number in the debit accumulator, and the total contacts associated with the credit accumulator are disabled while the total contacts in the debit accumulator are made effective to control the printing of the balance. Should the highest order debit wheel stand at nine, the balance is printed under control of the total contacts closed by the credit accumulator wheels. In the printing of the balance from either set of wheels, the wheels are rotated in the same direction as in adding, the wheels moving in synchronism with the rising type bars and the totaling cams closing the total contacts and stopping the type bars in positions dependent upon the amount previously registered in the accumulator. The totaling operation is initiated by energizing the accumulator magnets for meshing or clutching the wheels of the selected accumulator with the driving means. The time of energization of the magnets is determined by the closing of zeroizing or resetting contacts that are connected to the accumulator magnets of the selected accumulator during total taking. The zeroizing contacts are closed at the ten index position in the totaling cycle (i. e., at the time when the upper "0" type on the type bar is passing the printing line; the other type following in the order, 9, 8, 7, 6, etc.) energizing the accumulator magnets which then clutch the accumulator wheels to the driving means. Each wheel continues to rotate until at the zero position the totaling cam closes the total contacts and energizes a printer control magnet which in turn operates a latch to hold the related type bar in a position presenting a type for printing

the number accumulated in the wheel before the total taking operation.

The devices of the present invention differ from the above described Peirce devices as follows:

5 Only one set of total contacts is connected to the print controlling magnets. The total contacts associated with the credit accumulator wheels are used to control the printing of both positive and negative balances. The total contacts are closed by the cams on the credit accumulator wheels moving in the additive direction on positive balances and the subtractive direction on negative balances. In the printing of a negative balance, the debit accumulator is zeroized, and by means of the gear connections the credit accumulator wheels are driven in the reverse of the usual direction of movement, closing the associated total contacts at times complementary to the time of closing when moving to 10 print positive balances.

15 The wheel position reading contacts in the debit accumulator, corresponding in structure to the total contacts, are positioned differently and wired differently from the total contacts associated with the debit accumulator in the Peirce disclosure. The contacts are normally closed (i. e., with the debit wheel at nine) and open when the wheel moves to any position other than normal. The contacts are not connected to the 20 printer magnets. They are connected to the accumulator magnets and act to clutch lower order debit wheels for zeroizing in the taking of a negative balance. The contacts are electrically connected in series, and each contact has a series connection with related accumulator magnet, the several lines between contact and magnet being connected in multiple to the power source through a line including minus balance contacts. When taking a negative balance, the 25 lowest order debit accumulator magnet is energized by the closing of the minus balance contacts at the ten index position in the cycle to clutch the related accumulator wheel with the driver. Should the lowest order debit wheel stand in 30 normal position with the wheel reading contacts closed, the circuit contains another parallel line, and the tens order debit accumulator magnet is also energized at the ten index position. If the tens order wheel stands in normal position, the 35 circuit includes the hundreds order accumulator magnet. The connections continue across the entire debit accumulator to determine the number of lower order wheels, starting with the units wheel, that stand in normal position, and thereby 40 energize certain of the lower order debit accumulator magnets at the ten index position to clutch the wheels with the driving means and start the zeroizing of the wheels early in the negative balance printing operation. The higher 45 order debit wheels are connected to the driving means at the nine index position in the totaling cycle by devices for zeroizing in a manner about to be described.

50 Two sets of zeroizing or resetting contacts are provided for timing the energization of the accumulator magnets. Either set is effective on a total taking operation to control the connection of the accumulator wheels with the driving means and start the movement of the wheels to zero. 55 One set of zeroizing contacts is used to control the energization of the credit accumulator magnets and the other set controls the debit accumulator magnets on totals. The set associated with the debit accumulator magnets is delayed in 60 operation during the taking of a negative balance

65 to close at the nine index position in the totaling cycle (i. e., when the "9" type is passing the printing line) instead of the ten index point position. This is done to correct the number printed representing a negative balance. It causes the higher order printer devices to print numbers one digit less than if the debit wheels were clutched to start rotating at the ten index position. The reason why a correction is needed is because when the debit accumulator holds a 70 complementary amount and a debit amount is added thereto causing the accumulator to pass from a complementary reading to a true number, the carrying devices in the debit accumulator add a unit on each of the higher order debit 75 wheels. This carried amount—usually 11111110—does not truly represent any part of the debit amount. The unit step of motion of the higher order debit wheels is transmitted to the credit wheels and the related totaling cams are moved 80 one step towards the total contacts. Since the type bar is moved in synchronism with the credit wheel and total cam during totaling, the space between the total cam and the total contacts determines the magnitude of the number printed. 85 In order to print a corrected smaller number during negative balance printing the higher order type bar is allowed to move one step before the related debit wheel is clutched (at nine index point instead of ten index point) to the driving means 90 to start the totaling cam moving towards the total contacts. Since the undisturbed lower order debit wheels are not moved by a transfer, they may be zeroized at the ten index position as 95 pointed out hereinbefore. The printer magnets are energized as the total contacts close, and the type bars are positioned to print a true number representing the correct negative balance.

100 The devices of the present invention do not require connections from the highest order accumulator wheel to the lowest order wheel to carry an "elusive one" from the highest wheel to the lowest wheel.

105 From the foregoing it may be gathered that the mode of operation of the machine for total printing according to the present invention, differs from the Peirce type of operation in that both negative and positive balances are printed under control of contacts operated by the credit accumulator wheels; the need for the transfer of an "elusive one" from the highest order wheel to the lowest order wheel is dispensed with; the higher order debit accumulator wheels are clutched with the driving means an instant later in the totaling cycle to correct the negative balance printed under control of the credit accumulator wheels; and the time of clutching the lower order debit wheels for zeroizing in negative balance printing is varied according to whether one or more lower order wheels stand in 110 normal position.

115 An object of the invention is to provide an improved total printing device.

120 Another object is to provide means for printing negative and positive totals under control of one accumulator.

125 A feature of the present invention is the means for correcting total balance printing under control of an accumulator.

130 Another object is to provide a simplified circuit for electrically controlled printing devices. By the present invention a zeroizing circuit has connections to, and forms part of, a total printing control circuit.

135 Another object is to provide means for varying

the time of zeroizing or meshing of a portion of an accumulator during a total taking operation.

Another feature of the invention is the means for changing the amount to be printed under control of an accumulator wheel during total printing.

An object of the invention is to provide a means automatically controlled by an accumulating wheel for determining the time of meshing of another wheel for clearing during total taking.

By means of the present invention connections from a single printing device to a single accumulator serve to control the printing of totals from a plurality of accumulators.

Another object of the invention is to provide a pair of accumulators and connections between them enabling the one to control printing not only of the numbers standing on it but also the results of accumulations on the other accumulator.

Another object is to provide a duplex accumulator with improved means for printing positive and negative balances resulting from additions and subtractions of credit and debit items.

Another object is to provide means for printing a negative balance by reversing the direction of rotation of wheels adapted to print a positive balance; also providing means for correcting the result by governing the time of rotation of the wheels.

Another object is to provide means for sensing a plurality of wheels in an accumulator and adding a unit in one or more orders to fill out the balance in a subtractive system.

These and other objects will appear in the following description of the invention.

Referring to the drawings wherein I have shown what I now consider to be the preferred form of my invention,

Fig. 1 is a side view, partly in section, of the machine embodying the invention.

Fig. 2 is a similar view, the parts being shown in section to expose the interior of the machine revealing the printing mechanism and one of the duplex accumulator units.

Fig. 3 is a side elevation of one of the duplex accumulator units with portions broken away to more clearly disclose certain parts of the mechanism.

Fig. 4 is a side elevation of one bank of the debit accumulator.

Fig. 5 is a side elevation showing the total reading cam and total contacts of the highest order debit accumulator wheel.

Fig. 6 is a side elevation of the total control devices.

Fig. 7 is a side elevation of the zeroizing contact shifting device.

Fig. 8 is a plan view of the contact shifting unit showing the operating connections.

Fig. 9 is a front elevation of the duplex accumulating devices.

Fig. 10 is an illustration of the operation of the machine in printing positive and negative balances.

Fig. 11 shows the kind of a printed slip produced by the machine.

Fig. 12 is a wiring diagram of the machine showing the control of the accumulators for adding and subtracting and also the control of total printing.

Fig. 13 is a perspective view of an assembly frame carrying a pair of accumulators engaging pinions.

Throughout this specification it is to be understood that the capacity of the debit accumulator for addition is one order less than the number of orders provided. The highest order is reserved for testing for complements. Although most of the novel structural features are shown in Figs. 4, 5, 7 and 8, it is advisable to consider first the illustrative machine, as described hereinafter under the headings "The main drive", "The Duplex accumulator", "Carrying mechanisms", "Printing mechanism", and "Total taking devices", before explaining the novel structure and mode of operation used in performing negative balance printing according to the present invention.

The illustrative machine is of the type controlled by the well known Hollerith form of perforated card. The card is sensed by the analyzing devices of the machine and the amount represented by the perforations on the card is accumulated and printed. The card is fed through two sets of sensing brushes. The first set of brushes serves to compare the group number of a card with the group number of the card under the other set of brushes and if the numbers do not agree the machine may be stopped or a total may be taken automatically.

The first set of brushes also serves to sense the presence of a special perforation present on cards carrying perforations representing a debit item. The second set of brushes serves to control the accumulators and the printing devices.

In the Peirce machine used, two gear connected sets of accumulator wheels are provided; one set is adapted to receive and add credit item; the other set accumulates debit items. The credit and debit items are distributed under control of the upper or first brushes the card encounters as mentioned above. While one set of accumulator wheels is adding an amount, the other set of accumulator wheels is being rotated, by gearing connecting the two sets, in a direction which is the reverse of their normal adding movement, thus subtracting the amount from the number standing on said other set of wheels. The debit accumulator wheels are all normally set at nine, and as credit items are added on the credit accumulator they are subtracted from the debit wheel thus presenting the nines complement of a credit balance. If the debit items, however, amount to a larger figure than the credit items added, a number representing a debit balance will be held by the debit wheels, while the complement of the balance will appear on the credit wheels. The setting of the wheels may be reversed so that the credit wheels normally stand at nine. When a totaling operation is initiated, the highest order wheel in the debit accumulator is sensed to determine whether the wheel stands at nine or zero. If the wheel stands at nine a credit balance is printed under control of the credit accumulator. If the wheel stands at zero, the credit accumulator contains the nines complement of the debit balance which is present on the debit accumulator wheels as a positive number. Therefore control is exercised to print the total under control of the debit accumulator wheels that hold the balance as a result of the machine having handled debit entries that totaled a larger amount than the credit entries.

The main drive

As shown in Fig. 2 the machine is driven from an electric motor or other power source through a belt 1 mounted on a pulley 2 fixed on a shaft 3

15

20

25

30

35

40

45

50

55

60

65

70

75

having a worm 4 meshing with a worm wheel 5 on shaft 6. In Fig. 1 the shaft 6 is shown as having a gear 7 mounted thereon and meshing with the gear 8 which in turn meshes with a gear 9 on a shaft 10. Also mounted on this shaft is a bevelled pinion 11 meshing with a bevelled pinion 12 on a vertical shaft 13. Fixed on shaft 13 is a bevelled pinion 14 meshing with a bevelled pinion 15 fixed on a shaft 16 (Fig. 2) which reaches across the back of the machine. Also fixed on shaft 13 is another bevelled pinion 17 meshing with a bevelled pinion 18 fixed on shaft 19 (Fig. 2) which also reaches across the machine parallel to the shaft 16. Both the shafts 16 and 19 have fixed thereon a number of driving gears 20 (see Fig. 3). Each related pair of accumulator units is mounted on a plate 21 and is provided with a pair of intermediate driving gears 22 (Fig. 9). The units may be slid into position between upper and lower supporting plates 23 and 24 as shown in Fig. 2. When in this position each gear 22 meshes with one of the driving gears 20. When the machine is in operation the shaft 6 and also the shafts 16 and 19 are constantly turning. Thus the intermediate driving gear 22 of each accumulator unit will also rotate constantly.

Throughout this specification reference is made to CR and CF cam contacts. The CR cam contacts are operated continuously whether the machine is idling, adding, subtracting, or totaling. The cams for these contacts may be mounted on shaft 10 (Fig. 2) which is always turning. The other CF cam contacts are operated whenever cards are feeding. They are controlled by cams on a shaft that is made operative by the closing of a card feed clutch as explained hereinafter.

The duplex accumulator

As shown in Fig. 3 two accumulators are mounted on a common plate 21. The upper accumulator is normally set with its wheels at zero and is adapted to receive and add credit entries and at the same time, through gear connections, rotate the lower set of wheels in a reverse direction. The lower accumulator is normally set with its wheels at nine and is adapted to receive and add debit entries, simultaneously rotating the upper set of wheels in a reverse direction.

Since the accumulators are similar in construction except for the positioning of a few cams, a description of one applies as well to the other.

In the present Hollerith system the passage of the card under the sensing brushes is synchronized with the movement of the other mechanism so as to produce the proper differential action in accumulating and printing when an impulse is released under control of the card. Whenever an electrical impulse is initiated it may be sent through a corresponding accumulator magnet 25 (Figs. 2, 3 and 12) in order that the accumulator may be actuated to properly enter the amount therein. The energization of magnet 25 (Fig. 3) attracts an armature 26, moving it to the right thereby unlatching arm 27 of an assembly 330, mounted for oscillation on stud 28, the assembly being normally urged counterclockwise by spring 29. Therefore, when armature 26 releases arm 27 the assembly 330 is rotated slightly counterclockwise. This assembly 330 includes a pair of upwardly extending parallel arms 30 and 31, Fig. 13, in the upper ends of which is fixed a horizontal rod 32. On rod 32 there is mounted for rotation a sleeve 33 on which are fastened pinions 34 and 35. Pinion 35 is adapted to mesh with an accumulator gear 36 (see lower accumulator, Fig. 3) loose on

stud 37, and pinion 34 is aligned to mesh with a gear 38 fastened to the constantly rotating driving gear 22 (Fig. 9) so that whenever the assembly 330 on which the pinions are mounted is carried to the left (Figs. 4 and 13) in order to actuate the accumulator, the accumulator gear 36 will be connected to the constantly rotating gear 38 for rotation. Gear 38 is fast on a sleeve 39 which is loose on stud 37. Alongside of gear 38 and rotating with it on sleeve 39 is the intermediate driving gear 22 (Fig. 9) in mesh with driving gear 20 (Figs. 2 and 3) which we have noted is in constant rotation in timed relation with the card feed, being mounted on the constantly running shaft 16 or shaft 19. Gear 36 is one element of the accumulator wheel which is composed of gears 36 and 46, and cams 71, 210 and 213, riveted together and loosely pivoted on stud 37. Fig. 9 discloses a side view of the assembled accumulator wheels. From the diagrammatic showing in Fig. 13, the positions of the various gears may be noted and the train of connections may be traced from the driving gear 20, through intermediate driving gears 22 and 38, thence through the pinions 34 and 35 to the gears 36 and 46 on the accumulator wheel.

With the above construction in mind the differential action of the accumulator may be understood. When credit accumulator magnet 25 or debit accumulator magnet 40 is energized at a time determined by the position of a perforation on the card, the related armature 26 releases arm 27 permitting it to rock until arm 31 rests against a stop 630. This movement engages pinions 34 and 35 with the related gears 38 and 36 and causes the accumulator wheel to rotate in synchronism with the constantly rotating gear 38.

This rotation continues until a projection 41 on a cam 43 secured to sleeve 39 passes under finger 42 projecting from the upper end of arm 31, thereby rocking the pinion assembly 330 clockwise, disengaging the pinions from the gears and permitting armature 26 to latch arm 27. There are two projections 41 on cam 43, for the cam is timed to turn a half revolution for each operating cycle. Accumulating gear 36 is designed to turn through one-fourth of a revolution for each complete adding cycle of ten steps of movement. The distance through which accumulator gear 36 turns is dependent on the time of engagement and the duration of engagement of the gear with the constantly rotating gear 38. For example, to add the number "9" the two gears are connected for approximately a quarter of a revolution before the clutching pinions 34 and 35 are moved out of engagement with the gears. Pinion 35 is provided with a detent 44 to engage and locate the same when the pinions are moved out of engagement with the gears. To positively restore armature 26 a member 45 is provided having a projection abutting the right side of the armature 26 and a horizontal arm under arm 27 so that when arm 27 is restored the member 45 will be rocked counterclockwise to draw the armature away from the magnet if the spring 46 has not already done so.

The pinions 34, 35 and gears 36, 38 are formed with teeth resembling ratchet teeth. The sides of the teeth which enter into driving engagement with each other are cut with a radial flat face so that as a pinion is rocked into engagement with a gear and rotated, the tendency to throw the gear out again is not present as would be the case if gears having involute teeth were employed.

A means is provided for connecting the two accumulators for reverse rotation. The upper and lower accumulator wheels on the plate 21

are parts of separate accumulators, the upper wheel being in the credit accumulator, and the lower wheel being in the debit accumulator. Both wheels are in the same denominational order. Turning to Fig. 9 it is noted that alongside of gear 36 on each of the accumulator wheels is a gear 46. It is apparent that gear 46 is on the part of the accumulator unit which is differentially moved by pinion 35 when the pinion is rotated by the constantly revolving gear 38. In mesh with gear 46 on the upper accumulator wheel is a gear 47 (Figs. 3 and 9) mounted for rotation on a stud 48 projecting from a bracket 49 secured to the side of plate 21. In mesh with gear 47 is another gear 50 also mounted on bracket 49 with a stud 51. The gear 50 is in mesh with gear 46 on the lower accumulator wheel.

Thus the two accumulator wheels in a related order of the debit and credit accumulators are connected by gearing so that the movement of one will be transmitted to the other. Either set of credit or debit wheels is adapted to rotate in a counterclockwise direction when adding a received credit or debit item. However, since only one item is added at a time, the accumulator not receiving the item additively has its wheels rotated in a clockwise direction. If a credit card passes through the machine, magnet 25 is energized at the proper time and the upper accumulator wheel is rotated in the normal additive counterclockwise direction, while the lower wheel, by means of gears 47 and 50, will be rotated in a subtractive clockwise direction.

If a debit card passes through the machine, certain of the circuits are changed so that magnet 40 instead of magnet 25 is energized at the proper time, and the lower accumulator wheel is rotated in the normal additive counter-clockwise direction while the upper wheel, by means of gears 47 and 50, will be rotated in a subtractive clockwise direction. If a transfer movement is imparted to one of the wheels in the accumulator receiving the item entered, this movement also will be transmitted through gears 47 and 50 to turn the connected wheel a unit in the subtractive direction.

The amount of a credit item is added to the number on the wheels of upper credit accumulator and subtracted from the number in the lower debit accumulator. A debit item is added to the number on the wheels of the lower debit accumulator and subtracted from the number on the upper credit accumulator. In this way one of the accumulators will contain the balance as a true number while the other accumulator will hold the nines complement of the balance.

A common detenting device, positions and aligns both of the credit and debit accumulator wheels in a denominational order when the driving pinions 35 are disengaged from the gear 36. Normally the credit and debit assemblies 330 are latched by armature 26 in a position wherein both driving pinions 35 of an order are disengaged from the accumulator wheels. At this time it is advisable to hold the wheels from rotation until either assembly 330 is rocked to enter an amount. For this purpose a train of connections including a link 52 (Fig. 3) is provided. This link has pin and slot connections 53 with both arms 27. The slots are so arranged that the rocking of either assembly 330 to mesh pinion 35 will lift the link without disturbing the other pinion assembly. A pin 54 in link 52 engages a slot in the end of one arm of a bell crank 55 pivoted on a stud 56.

When the link is lifted, the bell crank is rocked in a clockwise direction, its vertical arm 57 pulling a horizontal detent link 58, pinned at 59, to the right (Fig. 3). The detent link at its left end has a slot 60 which enables the link to move freely back and forth on stud 48, at the same time being held in place on the unit by a headed screw in the stud. A single toothed detent member 61 is riveted to link 58 in a position where it is normally inserted between two teeth on the gear 47, thus holding this gear from rotation and since both the upper and lower accumulator wheels are connected by gearing with gear 47 they are also held in position and aligned by detent 61. The bell crank 55 is in the form of a bail and has another horizontal arm 62 to which is attached one end of a spring 63 urging it in a counterclockwise direction. This spring serves to normally hold detent 61 in engagement with gear 47. When either assembly 330 is rocked to mesh pinion 35, link 52 is lifted, crank 55 is rocked, and detent 61 is withdrawn from the teeth of gear 47 so that both accumulator wheels may be rotated.

The spring clips 64 shown on many of the members in Fig. 3 are provided for the purpose of aiding in the assemblage and removal of parts. They are made of spring material and are secured at one end to a member while at the other end they are offset and carry a short pin which is part of the linkage. The pin may be disengaged from a connected link by lifting the end of the clip away from the member.

Carrying mechanisms

35

For effecting carrying or transferring from one order to the next higher order a brush 65 (Figs. 3, 5 and 9) fixed to an arm 66 pivoted at 67 is adapted to cooperate with a segmental extension 68 on a commutator or disk 69 mounted on stud 37 and attached to constantly rotating gears 22 and 38. Each commutator disk 69 has four segmental extensions 68, 79, two segments 68 in one plane cooperating with brush 65 and the other two segments 79 in an adjacent plane cooperating with brush 78. When an accumulator wheel of a given order passes from its nine position to its zero position, a projection 70 (Fig. 5) on cam disk 71 fixed with respect to the gear 46 will engage a projection 72 on the arm 66 and rock the arm clockwise into the position for carrying.

The latching pawl 73 pivoted on a stud 82 on frame 21 will then cooperate with a projection 74 (see Fig. 3) on the arm 66 and latch the arm in this position so that the brush 65 will be in position to make contact with the commutator segment 68 when the latter, which is on the constantly rotating disk 69, passes the brush.

This contacting of brush 65 with segment 68 will take place soon after the projection 74 associated with the accumulator wheel of the next higher order has engaged the arm 42 and cammed the pinion 35 out of mesh with gear 36. The contacting of brush 65 with segment 68 will supply current through disk 69, to the contact brush 75, Figs. 3, 9 and 12, touching either extension 79 on disk 69 during the transferring, and then to the magnet 25 or 40 of the adding unit of the next higher order as described hereinafter. On energization of the magnet, pinion 35 will reengage and turn gear 36 one more step and then be cammed out by cam point 415. If the value standing in the wheel of any accumulator order happens to be nine when one is 75

added to that order causing the adding wheel to pass from the nine position to the zero position, it will be necessary to continue the carrying on to the accumulator wheel of the next higher order. In order that this may be effected when the wheel 46 of any order stands at the nine position, its disk 71 will present a depression 76 to the arm 72 as in Fig. 5, permitting the arm to be rocked counterclockwise by its spring 77 into the position of Fig. 5 rocking the brush 78 also carried by the arm 66 into position to be engaged by a commutator segment 79 also on the disk 69.

The brushes 65 and 78 are insulated from each other and current is supplied to them through separate wires but both brushes are adapted to carry current to the disk 69 and through the contact brush 75 to the accumulator magnet 25 or 40 of the next higher order.

The segment 68 engages the brush 65 at the same time that the segment 79 is adapted to engage its brush 78. Thus if the accumulator wheel of a given order passes to zero position and supplies current to the brush of the accumulator unit of the next higher order, if the latter unit contains the value nine, it, besides being caused to accumulate an additional one by reason of the position of the brush 65 in the unit of the next lower order, will supply current through its brush 78 to the unit of the next higher order to carry one thereto.

Of course, if the cam disk 71 of a given order is standing in its nine position, as in Fig. 5, as soon as one is added to this order, the cam disk 71 will turn one more step to the position of the upper wheel in Fig. 3. This will rock the brush arm 66 to the carrying position, but current will have been already supplied through brush 78 to perform the carrying function in the next order. The rocking of the arm 66 to this position to cause the brush 65 to be engaged by its commutator segment 68 will have taken place too late to effect the carry in the next higher order. It is for this reason that the brush 78 is provided. The rocking of the brush 65 from the nine to the zero position thus has no effect and it will be restored to normal position before the next segment 68 reaches it. After the brush arm 66 has been rocked to the carrying position and latched by the pawl 73 and after the segment 68 has passed the brush 65, the arm 66 is released by a projection on cam 80 (Figs. 3 and 9) engaging the inner projection 81 of the latching pawl arm 73 which is pivoted at 82, rocking the pawl against the tension of spring 83 and releasing the arm 66 to permit its spring 77 to rock it counterclockwise until the projection 72 engages the periphery 84 of the disk 71.

The arm 66 will then be in such a position that neither brush 65 nor brush 78 will make contact with the disk 69.

Although both the upper and the lower accumulators are provided with carrying mechanisms, only the carrying devices in the accumulator receiving the item are effective during an operation of the machine. The other carrying devices associated with the accumulator being driven in a reverse direction by the transmission gears 47 and 50, may trip mechanically but they are disabled by breaking the circuit through the transfer devices in a manner to be described further on in this description in connection with the wiring diagram. Of course, the transfer movements imparted to the accumulator receiving the item entry will be transmitted in a reverse

direction to the other accumulator just as the regular differential movements are transmitted.

Printing mechanisms

The printing mechanism includes a platen 116 (Fig. 2) and a type carrier 117 having a plurality of type elements 118 adapted to be struck by a hammer 119 loose on a rod 120. The type carrier is connected at its lower end to an arm 121 fulcrumed at 122. Springs 123 connected to the arms 121 and to a cross beam 124 connected between arms 125 pivoted at 126, tend to raise the arms 121 to raise the type carriers. A restoring bail 126' connected by links 127 to arms 125 is adapted to restore the arms 121 to 15 their lower or normal position. An arm 128 (Fig. 1) fixed to the shaft 126, on which the arms 125 are also fixed, is connected by a link 129 to a complementary cam follower arm 130 pivoted at 131 and cooperating with cams 132 and 133 on 20 cam shaft 134.

Shaft 134 is driven through a chain of gears 135, 136 and 137, the latter of which is mounted on shaft 6. The shaft 134 turns synchronously 25 with the feeding of the cards through the machine, and the bail 126' (Fig. 2) is thus raised so as to permit the type carrier to rise synchronously with the feeding of the card. Thus when the type element 118 carrying the numeral 9 is approaching the printing line with respect to platen 116 and the actuating hammer 119, the nine position on the card will be passing the reading brushes 90, Fig. 12, as described hereinafter with reference to the wiring diagram.

If there is a hole in the card at the nine position, a circuit will be closed through the brush 90 to the printing magnet 108 (Fig. 2) of that particular column. This will attract the armature 138 actuating a rod 139 which is connected to a latching member 140. This will release the 40 latching pawl 141 permitting it to cooperate with the ratchet teeth 142 carried by the type carrier to stop the type carrier with the 9 type in line for printing. When the arms 125 raise the bail 126' to permit the type carriers to rise, the spring 123 will be stretched so as to raise the arm 121 of the type carrier. After printing has been effected, the arms 125 are then lowered with the bail 126' to restore the type carriers to normal 45 position.

The latching pawls 141 must then be restored before the type bars begin their next upward movement. For this purpose a bail 143 is adapted, when rocked clockwise, to rock the latching pawl 141 counterclockwise against the action of 55 its spring and permit it to be latched by the latch 140. The bail 143 is connected by links 144 to arms 145 fixed on shaft 146 on which is also fixed an arm 147 (Fig. 1) connected by link 148 to an arm 149 pivoted at 150 and connected to a cam 60 follower arm 151 (Fig. 2) carrying a roller adapted to be actuated by a cam 152 on shaft 134.

The several type actuating hammers 119 are actuated by individual springs 153 tending to rock them against the type 118 to effect printing. 65 The hammers are normally locked in their inoperative position by individual latches 154. These latches are connected to levers 155 normally held up by pins on the type bars, but adapted to operate the lowered levers 155 and 70 trip latches 156 to be moved to the left by a bar 157 when the rising of the particular type carrier 117 permits the arm 155 to rock counterclockwise into a position to be actuated by the bar 155.

The bar or bail 156 is pivoted at 157 and is con- 75

nected to an arm 158 (Fig. 1) connected by a link 159 to a bell crank 160 in turn connected by a link 161 to an arm 162 fixed at 162a to a shaft which carries (see Fig. 2) a cam follower arm 5 162b having rollers 162c cooperating with complementary cams 162d mounted on shaft 134. The bail 163 which restores the hammers to normal position is fixed on the shaft 120 with the arm 160 (Fig. 1). The pin and slot connection 10 159' between link 159 and arm 158 permits the shaft 120 to turn clockwise far enough to move the bail 163 out of the way of the hammers 119 before the arm 158 and bail 156 are actuated to release the hammers.

15 When listing is to be effected on the listing sheet while the data is also being accumulated, the printing magnet 108 will be connected to receive an impulse through the perforation in the card simultaneously with the transmission of such 20 impulse to the accumulator magnet 25 or magnet 40. The amount may be listed whether the item is a debit or a credit. A plus or minus sign may be printed adjacent the item to classify it as a debit or a credit.

25 Total taking devices

When a total is to be taken of a group of items which have been accumulated, it is necessary to open certain listing circuits and close certain 30 total printing circuits. The mechanism for effecting these circuit changes is shown in Fig. 6 in which a magnet TSM is adapted to be energized whenever a total is to be taken. Suspended from the machine base 94 (Fig. 2) is a pair of brackets 35 95 supporting a series of contacts arranged in tiers for compactness. Each group of contacts comprises an upper blade 96, Fig. 6, a center blade 97 and a lower blade 98. Cooperating with these fixed blades are blades or contacts 99 and 100 40 mounted between horizontal insulated strips fastened at the ends to vertical bars 101 (Fig. 2) supported by arms 102 secured to shafts 103 and 104 journaled in brackets 95. The rocking movement of arms 102 is transmitted through bars 45 101 to raise and lower contacts 99 and 100. A spring 103' attached to an arm 102' on one end of shaft 103 tends to urge bars 101 downwardly from their normal, or listing position, wherein the blades 96 and 99 are in contact with each 50 other.

The contact formed between blades 96 and 99 is lettered TSA, and the other normally open contact between blades 97 and 99 is designated TSC. Other contacts between blades 98 and 100 are 55 of a general form designated in different ways TSD, TSI, TS2, TS5 and TS6 at different points in the wiring diagram as pointed out hereinafter.

At the one end of shaft 103 (Fig. 6) arm 102 carries a link 107 which forms a toggle connection with a link 165 pivoted at 169. This toggle connection is held with its common connecting point slightly to the left of dead center, as shown in Fig. 6, by the action of the spring 103' on the arm 102' attached to shaft 103. An adjustable stop 170 limits the movement of the parts to the left. Energization of magnet TSM attracts its armature 171 rocking it about its pivot 172 to unlatch an arm 173' on a hammer 173 which, under action of spring 174, strikes the toggle at its 65 connecting point and moves it sufficiently to the right of dead center to allow spring urged shaft 103 to further move the contacts to total circuit closing position.

A double armed lever 179 secured to shaft 103 70 and having a roller 181a moves to engage its

cam 180 on continually running shaft 10 immediately upon breakage of toggle 107, 165 permitting a link 181 to rock a latch 182 against the tension of spring 185 and out of engagement with the toe of an arm 183 fast to a rock shaft 184. 5 The aforementioned hammer tripping takes place at a time when cam 175 secured to continually running shaft 10, is about to present its descending portion 176 to a roller 177 mounted on an arm 178 loosely pivoted on shaft 103. The 10 arm 178 is urged upward by a spring (not shown) and connected by a link 187 to arm 183 abutting against latch 182. When the latch is operated as described, arm 178 is free to rise and place roller 177 in cooperation with cam 175. As 15 roller 177 then follows the periphery of portion 176 of cam 175 it permits shaft 184 to rock clockwise (in Fig. 6) through link 187 attached to arm 183, since latch 182 is now out of cooperation therewith. Continued rotation of shaft 10 20 causes cam 188 to cooperate with a bell crank lever 189 loose upon shaft 103 and held against cam 188 by spring 190. At such a time, cam 180 has restored shaft 103 to almost normal position from which a roller 191 on lever 189 moves toggle 25 107, 165 across dead center and against stop 170. The lever 189 carries another roller 192 which strikes finger 193 integral with hammer 173 to restore the same.

In Fig. 1 it is shown that shaft 184 has connections to a similar shaft 184 through link 194 and arms 195 so that both shafts operate together. These shafts extend across the accumulating sections of the machine and have grooves 196 cooperating with the ends 197 of levers 35 198 (see Figs. 3 and 4) pivoted at 198a on the accumulator unit plates 21. At the right end of lever 198 is a link 199 having pin and slot connection 200 (Fig. 4) with the lever. With the parts in the position shown in Fig. 3 link 199 is 40 held in its raised position. But during total taking with shaft 184 rocked, the link 199 is lowered as seen in Fig. 4.

Resting in slots 201 in link 199 are pins 202 on the free ends of upper and lower horizontal 45 arms 203 pivoted on plate 21 as at 204, Fig. 4. Also on the free ends of arms 203 are fulcrum blocks 205 in contact with the under side of springs 29. When the parts of the accumulator are in normal position (i. e., in position for item 50 entering as in Fig. 3) arm 203 is held in raised position by vertical link 199 and lever 198 one end of which is held down by the shoulder on shaft 184. Underneath a projection 2051 on arm 203 is a latch 206 on the lower end of arm 207 55 pivoted at 208. Integral with arm 207 is an upwardly extending arm 209 having its free end in the path of cam 210 fast to gears 36, 46 (see Fig. 9). The cam 210 has four projections which act to disengage latch 206 when the accumulator 60 wheel is at zero.

While arm 203 is in the normal position, the free end of spring 29 is pressed upwardly by fulcrum 205 and serves, as already explained, to swing the assembly 330 in a counter-clockwise 65 direction to carry out the adding operation. With the parts conditioned for totaling by operation of shaft 184 and release of lever 198, link 199 and arm 203 as explained hereinbefore, the arm 203 is held in raised position only by the engagement of its lateral projection 2051 with latch 206. So that when arm 209 is raised by cam 210, latch 206 is withdrawn from underneath lever 203 which thereupon drops sufficiently to release pressure of fulcrum 205 on spring 29 which then fol- 70 75

lows the fulcrum downwardly and rotates the assembly 330 clockwise instead of counterclockwise.

In other words, spring 29 tends to rotate the assembly 330 in one direction when fulcrum 205 is elevated and in the other direction when the fulcrum is lowered. This by reason of the fact that with fulcrum 205 released and resting on arm 211, spring 29 bears upon fulcrum 205 and depresses arm 211 of lever 27 on assembly 330 with greater turning effort than is exerted, in the opposite direction by the end 212 (Fig. 3) of spring 29 at the point where the spring fits in a slot in lever 27, thus tending to turn the assembly 330 in a clockwise direction. This action, as will be explained, takes place to clear the accumulator wheel after total printing.

A totaling cam 213 (Figs. 3, 4 and 5) is provided with four raised cam portions 214. This cam is fast to transfer cam 11 and gear 46 as may be seen in Fig. 9. The cam therefore, has four zero positions. Cooperating with cam 213 is a bell crank 215 pivoted at 216 and having the lower end 409, Figs. 4 and 5, of the vertical arm projecting into the path of the raised portions 214 on cam 213. The shape of the end 409 and portion 214 allows movement of the accumulator wheel in either direction. The other arm of crank 215 has fastened to it an insulating block 410 cooperating with the underside of a contact spring 411. This contact 411, and an upper contact 412 insulated from it, are part of a circuit closed during a totaling operation. The cam 213 is adapted to move bell crank 215 in a counterclockwise direction, lifting contact 411 and closing points TC, see Fig. 12. The bell crank and cam are so arranged that when a credit accumulator wheel stands at zero, the projecting end of the vertical crank arm stands on one of the raised portions 214, Fig. 4, and contact points TC are closed. The TC contacts associated with the debit wheels are closed in the normal nine position of these wheels. In Fig. 12 it may be seen that a series of contacts TC cooperate with wheels 213 in the upper credit accumulator, and another series of contacts TC cooperate with wheels 213 in the lower debit accumulator. The credit contacts are connected in the total printing circuit while the debit contacts are used in accumulator zeroizing control during total taking.

The totaling contacts B1 (Figs. 5 and 12) are provided for the purpose of testing whether the total to be printed is a negative or positive balance. These contacts B1 are similar in construction and mode of operation to the contacts TC, the differences being that contacts B1 are in a different circuit, they are timed differently and the accumulator wheel with which they cooperate is the highest order wheel in the debit accumulator. The cam 213 on the highest order wheel (Fig. 5) is positioned to close contacts B1 when the wheel is at zero instead of closing at nine as the TC contacts which are operated by cams on all lower order wheels.

These contacts are used for controlling the printing of a total where the amounts added and subtracted yield a negative balance. That is, where the sum of the various amounts subtracted is greater than the sum of the various amounts added in the machine.

Where the total is a positive total, the highest order wheel in the credit accumulator will contain a zero and the corresponding debit wheel cooperating with contacts B1 will contain a nine, therefore contacts B1 will remain open as shown in Fig. 12, and the circuits, through which the

zeroizing impulses are directed to mesh the accumulator wheels in totaling, will send the current through the credit accumulator so that a total representing a positive balance will be printed under control of the credit accumulator. Where the total is a negative total, the highest order wheel in the credit accumulator will contain a nine and the highest order debit accumulator wheel cooperating with contacts B1 will contain a zero, therefore contacts B1 will be closed and on taking totals will serve to energize a minus balance magnet MBM (Fig. 12) which shifts certain total zeroizing control contacts so that the lower wheels are meshed at the proper time and a total representing a negative balance will be printed by the TC contacts closed by the credit wheels rotating under control of the debit accumulator. The circuit through magnet MBM leads from the one side of the line 230, through wire 250, cam contact CR6, wire 251, contacts TS1 now closed, magnet MBM, contacts B1, and wire 253 to the opposite side of the line 240. The contacts affected by the magnet MBM are adjusted so that the zeroizing impulses, sent through the accumulator magnets 25 or 40 to initiate the totaling operation, as explained further on, are directed to the proper accumulator.

For this reason contact blade 235 is moved by magnet MBM so that contact MBD is closed and contact MBE is opened, thus initiating the totaling operation in the debit rather than the credit accumulator.

The present invention provides means whereby both negative and positive totals are printed under control of the one credit accumulator. When a negative balance is being printed from type bars stopped differentially at times controlled by the contacts made by the credit accumulator wheels rotated under control of the debit wheels, correction must be made for altering the time of closing of the totaling contacts. This is done by delaying the time of zeroizing of the debit accumulator wheels during the taking of a negative balance. In order to correct the printing, two sets of zeroizing contacts are provided (see Fig. 12). The one set 1CC, when conditioned for totaling directs the zeroizing impulses through the credit accumulator at a time corresponding to the ten index position in a cycle, i. e., one position before the index position at which a "9" is sensed when entering items. This is the normal resetting operation and zeroizing occurs at the usual time without any need for correction. Another set of zeroizing contacts 2CC are designed to be closed at a time corresponding to the nine index point position to direct the zeroizing impulses through the debit accumulator magnets an interval of time later than the usual zeroizing time, during negative balance printing.

In Fig. 12 it may be noted that both sets of zeroizing contacts are connected in a circuit directed through both sets of accumulator magnets and also through the total printing contacts and the magnets controlling printing. The contacts are controlled by a mechanism to insure the proper timing of the zeroizing impulses.

In Figs. 1, 7 and 8 the mechanism for controlling the closing of the zeroizing contacts is shown. A pair of magnets control the device. The one magnet 1CM (see also Fig. 12) is energized during total taking for control of positive balance printing. When the minus balance magnet is energized the other magnet 2CM is energized and serves to control the closing of contacts 75

tacts 2CC during total printing for the registration of a negative balance.

In Fig. 1 it may be noted that a gear 9 is mounted on the constantly rotating shaft 10. This gear meshes with an idler gear 567 which in turn drives a gear (not shown) on shaft 569. Mounted on the end of shaft 569 is a cam 594 which serves to govern the time of closing of the zeroizing contacts 2CC.

Referring again to Fig. 12, it may be noted that a contact member 435 is shifted under control of the minus balance magnet MBM. When the minus balance magnet is not energized, indicating that a positive balance is to be printed, the circuit is made during totaling through the contacts MB5C energizing magnet 1CM. When contacts B1 close and the minus balance magnet is energized, it serves to shift contact member 435 so as to close contacts MB5D, directing current through magnet 2CM.

In Figs. 7 and 8 the relationship between magnets 1CM and 2CM and the mechanism for closing the zeroizing contacts may be noted. Magnet 2CM controls the shifting of the movable contact blades 2CC while magnet 1CM controls the shifting of the other upper zeroizing contacts 1CC. In Fig. 7 the contacts 2CC are shown as having their upper blades mounted upon cross bars carried by side plates 590 which in turn are carried by four arms 591 (Fig. 8) of which the upper pair of arms are secured to a shaft 592 while the lower pair of arms are free upon a shaft 592a. The other movable set of upper blades 1CC are mounted in a similar fashion alongside contacts 2CC. The lower sets of blades 1CC, 2CC are mounted between insulated blocks 900 held fixed in position on the frame of the zeroizing unit. The shaft 592 carries a loosely pivoted cam follower arm 593 having a roller cooperating with the cam 594 mounted upon the shaft 569 mentioned hereinbefore.

A spring pressed arm 595 forming part of follower 593 tends to keep the follower roller into cooperation with the cam 594. The arm 595 is connected by a link 596 to an arm 597 secured upon a shaft 598 which shaft also carries an arm 604 which supports a link 603. The upper end of the link 603 is slotted to receive a pin on an arm 602 which is fixed on the shaft 592 carrying the arms 591 and the 2CC contact frame. Through this linkage of arm 593, arm 595, link 596, arm 597, shaft 598, arm 604, link 603, arm 602, shaft 592, and upper arms 591, the frame carrying the upper contact blades 2CC is restored and held raised with the contacts open, as shown in Fig. 7, as long as the follower roller rests on the elevated portion of cam 594. The lowering of the frame depends on two releasing actions; the fall of the follower off the high part of the cam and the energization of magnet 2CM.

In addition to the linkage just traced, there is another linkage for holding the 2CC contact frame in a raised position under control of the magnet 2CM. Loosely pivoted on the shaft 598 is a release lever 599 the left end of which (Fig. 7) cooperates with the armature 600 of magnet 2CM. The right end of the lever is connected to the lower end of a link 498 (Fig. 8) similar to link 596 (Fig. 7) in outline. The upper end of link 498 is connected to an arm 499 (Fig. 8) fixed on shaft 592. Thus, the contact frame 590 is held in a raised position by the linkage composed of arms 591, shaft 592, arm 499, link 498, lever 599 and armature 600. The support is formed by the arm 599 normally held in the position of Fig. 7 by the

cooperation of its hooked end with a notch in the spring pressed pivoted armature 600 of the magnet 2CM. At the time when magnet 2CM is energized, the follower arm 593 is being held in its position as viewed in Fig. 7 by the rise on cam 594 which through the linkage to shaft 592 will rock the arm 599 slightly clockwise to remove the frictional pressure of its hooked end from the armature 600 to allow the free movement thereof should magnet 2CM be energized. When the armature 600 is attracted and arm 599 is released, the contacts 2CC are not closed since arm 593 is resting upon the rise on cam 594. However, continued rotation of cam 594 will permit the shaft 592 to turn in a counterclockwise direction through the connecting linkage. As the roller on arm 593 drops off the shoulder on cam 594, the resulting counterclockwise turning of the shaft 592 permits the contacts 2CC to be closed at the proper time which in this case is the instant corresponding to the nine index point position in the cycle. From the above description it may be gathered that the zeroizing impulse through the 2CC contacts is delayed by the cam 594.

In Figs. 1 and 8 is shown the other magnet 1CM which when energized causes the rocking of the armature 600a and release of the armature controlled arm 599a (Fig. 1) which is secured to the shaft 592a. The released arm 599a is rocked in a clockwise direction carrying along therewith a pair of arms 591b also fixed to shaft 592a. The movable contacts 1CC are controlled from the shaft 592a and are mounted on plates 590a (Fig. 8) carried by pairs of arms 591a and 591b. The upper arms 591a are loose on the shaft 592 and guide the frame carrying contacts 1CC without being influenced by the rocking of this shaft when it operates contacts 2CC, but the lower arms 591a are fixed to the shaft 592a for operation. From observation of Fig. 8 it is evident that the sets of fixed and movable contact blades 1CC are similar to blades 2CC in construction and arrangement. The contacts 1CC are restored manually at the same time that the total key 296 is depressed to take a total as described more fully hereinafter. Energization of the magnet 1CM will cause rocking of the shaft 592a and the lowering of the plates 590a controlled by this shaft and also the closing of the contacts 1CC. The closing of these contacts is arranged to occur at an instant corresponding to the ten index position in the cycle. It will be noted that the closing of the contacts 1CC is not delayed.

During the zeroizing of an accumulator, when performing total printing of the negative balance, other corrections must be made. Any lower order wheels in the debit accumulator which have not been disturbed by the addition and subtraction of numbers should start zeroizing at the ten index point position rather than the nine position. The wiring of the zeroizing circuit and the other arrangements made to take care of this correction of the lower order debit wheel resetting during negative balance printing may be noted from the view in Fig. 12. There it is noted that the contacts TC associated with the debit accumulator wheels are normally closed and are wired in series with each other. The contacts TC associated with the lowest order wheel are connected to a pair of contacts MB6 also having connections to the zeroizing circuit of the lowest order accumulator magnets 25 and 40.

The contacts MB6 are closed by the minus balance magnet MBM during the total taking of a negative balance. When the contacts are closed

a circuit is directed not only through the lowest order accumulator magnet but a connection is also made to the TC contacts associated with the lower order wheel. If the wheel happens to be standing 5 in its normal or nine position, the contacts TC are closed and the zeroizing impulse is directed further through the tens order accumulator magnet.

The connections continue across the debit 10 accumulator so that if the tens order debit wheel stands in its normal position, the zeroizing impulse will be directed through the hundreds order 15 accumulator magnet, and so on. The zeroizing impulse through the contacts MB6 is initiated at a time corresponding to the ten index position 15 in the cycle.

When it is desired to take a total, magnet TSM is energized to rock shafts 184 and also shift the contacts described in connection with Fig. 6. Contacts TS5 (Fig. 12) are also closed at this 20 time, one of their blades being fixedly mounted and the other being movable having such relations as blades 98 and 100 already described.

The items and totals printed may be accompanied by designating minus and plus signs, see 25 Fig. 11. An extra type bar and a control magnet 405, Fig. 12, is provided for such sign printing. The circuit through magnet 405 for printing a plus sign is from line 230, wire 350, contacts PM2, timed to close shortly after the beginning of 30 the cycle, wire 351, jack J1, plug wire to jack J8, magnet 405, bar 248 and wire 249 to line 240. Thus the type bar is permitted to move one step before being stopped with a plus type thereon opposite the printing line. When a debit item 35 or a negative balance is printed, magnet SBM or magnet MBM will act to close contact S36 or MB37 in the sign printing circuit so as to direct a circuit through the normally closed contacts PM1 to energize magnet 405 immediately 40 to stop the type bar in its lowest position in readiness for printing a minus sign.

In order to print an asterisk as a total identifying sign, devices may be provided including an extra type bar holding the special type, and a 45 magnet for controlling the type bar. The circuit through the magnet may be closed by any totaling contact.

A pair of make and break cam contacts CR2 and CR3 are arranged to operate to transmit an 50 impulse for total taking or zeroizing at a time one point in advance of the nine index point position in the cycle. These cams are mounted on a continually operating shaft driven by gear connections to the continually running shaft 10. 55 They also serve to close the circuit to the totaling contacts TC associated with credit wheels during a totaling cycle for the purpose of energizing the printing magnets 108. Contacts CR2 close first at ten index point and contact CR3 60 closes thereafter, they both remain closed for ten points of the cycle after which they both open, contacts CR2 first, followed by the sudden opening of contacts CR3.

With contact blades 96, 97, 98, 99, 100 shifted 65 from the position of Fig. 6, contacts CR2 and CR3 function to send an impulse through either accumulator early in the total cycle, current flowing from right of line 230, through contact TS5 now closed, contacts CR2, CR3, through wire 70 311, contacts MB6, wires 312, 313 and 314, or through contacts 2CC, wires 318 and 312, or through contacts 1CC and wires 318, 312 in a manner to be described more fully hereinafter under the heading "Totaling operation", contacts TSD now closed, the blade 235, through 75

either MBE or MBD according to whether the total is a minus or plus balance, through wire 236 or 237, magnets 25 or 40, bus bar 238, wire 239, and back to the other side of the line as represented by wire 240.

This energization of magnets 25 or 40 engages for rotation all the credit or debit accumulator wheels which are not already standing at normal position. For it is to be observed that with cams 210 and 213 at normal position (zero for the 10 credit wheels and nine for the debit wheels) the parts are positioned as shown in Fig. 4 with arm 203 dropped so that fulcrum 205 rests upon arm 211. Obviously, when magnet 40 is now energized, arm 30 will not turn counter-clockwise to 15 connect the accumulator wheel with the driving gear.

During the rotation of the accumulator wheels the type bars are rising in synchronism with the movement of said wheels, which in this instance 20 may be considered to be the cams 213. The motion of each type bar is arrested by an impulse through its printer magnet 108, through a circuit from right side of line 230, the zeroizing contacts, the upper TC contacts closed differentially, cable 25 245, to contact TSC now closed to printer magnet 108, bus bar 248, wire 249 to opposite side of line 240.

Thus, such accumulator wheels which represent a significant figure will rotate with one of 30 their cam surfaces 214 approaching bell crank 215, to close contact TC and to send an impulse at a differentially timed instant to control total printing just as in item printing a differentially located perforation in a card column closes a circuit to a printer magnet. Simultaneous with the arrival of cam 214 at normal position, cam 210 rocks arm 209 clockwise to throw the accumulator driving elements out of operative engagement, leaving the accumulator wheel in a reset or normal position, in a manner already described in connection with Fig. 3. The position of the cams 210 on the upper and lower wheels provides for the return to normal conditions, namely; the upper credit wheels to zero and the lower debit 45 wheels to nine, regardless of whether the credit or debit accumulator magnets control zeroizing.

In Fig. 10 there are shown a few examples of the operation of the accumulators in controlling the printing of positive and negative balances. 50 The numerals on the chart in Fig. 10 indicate the various positions occupied by the carrying cams and the wheel position sensing contact cams in both accumulators and also the movement of the type bars under control of the credit accumulator wheels during totaling. It is noted from the top line on the chart that normally the carrying wheels in the debit accumulator all stand at nine while the carry wheels in the credit accumulator stand at zero. It is also noted that the contacts TC associated with both accumulators are all normally closed with one exception, that being the highest order contact in the debit accumulator. The contact associated with the highest order debit accumulator wheel is normally open and is only closed when the wheel stands at zero, indicating that a negative balance is present in the accumulator in the form of a positive or true number on the debit accumulator wheels.

Assuming now that by means of the series of adding and subtracting operations or adding operations alone, a number 325 appears in the accumulator. The first operation performed in taking a total is to test the highest order debit 70 75

wheel which in this case indicates that the amount standing in the accumulator is a positive balance. The wheels in the credit accumulator are all connected with the driving gears at 5 the ten index position and continue to revolve in the adding direction. It may be noted from the numbers appearing in the fifth column on the second line of the chart that the cams attached to the wheels in the credit accumulator engage 10 the contacts TC after movement of 0, 7, 8, and 5 steps respectively, starting with the highest order cam.

These cams when rotated by the accumulator actuating members during totaling will keep in 15 synchronism with the movement of the type bar, the highest order cam stopping the highest order type bar immediately at its upper zero. The hundreds order cam will allow its type bar to move 7 steps thus presenting a 3 type to the 20 action of the printing mechanism. The tens and the units order cams move 8 and 5 steps respectively, thus allowing the tens type bar to rise to the 2 type position and the units type bar to rise to the 5 type position. The amount printed will 25 be 325 which is the correct positive balance standing in the accumulator. By this operation both accumulators will be restored to their normal position, the credit accumulator standing at zero and the debit accumulator standing at nine. 30 The third line on the chart assumes that other conditions prevail. Here it is noted that the total amount is a negative balance of 325. When the highest order debit wheel is now tested it is found that the wheel stands at zero thus indicating that 35 a negative balance is present in the accumulator. In the fourth column on the chart, third line, it is noted that because of the reverse rotation produced by the adding of the debit amount in the debit accumulator, the carrying cams in the 40 credit accumulators stand at 9675. Since the credit accumulator is about to be rotated in the reverse of its usual direction of movement the totaling cam is positioned from the contacts TC a number of steps represented by the figures in 45 column 5, line 3 on the chart. There it is noted that the units cam is 5 steps removed from the contacts, the tens cam is 3 steps removed from its contacts, the hundreds cam 4 steps, and the thousands cam 1 step.

50 Thus if no correction was made for the printing of the debit balance from the credit wheels, the amount printed would be 1435. The figure in the units order would then be correct but all the higher orders would print a figure one unit 55 in excess of the proper amount. In order to remedy this condition, all the orders higher than the units order are clutched for zeroizing at the nine index position during the total printing of the negative balance, thus allowing the type bar 60 to rise through one step of movement before the debit wheels are meshed for rotation. In this case it should be remembered that the type are arranged on the type bar with the larger numbers on top, the type being presented in the following order: 0, 9, 8, 7, 6, 5, 4, 3, 2, 1, 0. The units order debit wheel is clutched for zeroizing at the ten index position in the usual way because it does not need any correction.

70 Looking now at the sixth column and third line of the chart, it is noted that the movements of the type bars are arranged so that the units bar is stopped after 5 steps of movement. The tens bar would normally be stopped after 7 steps of movement but due to the late zeroizing of the 75 related wheel at the nine index position it is al-

lowed to move an extra step so that it moves a total number of 8 steps. Therefore, this type bar presents a 2 type for printing at the printing line. The thousands and hundreds type bars are also allowed to partake of an extra step of movement, thus moving 10 and 7 steps respectively instead of 9 and 6 steps. When all the type bars are stopped in position for printing the number printed will appear as 325 which is the correct negative balance printed under control of the 10 credit accumulator wheels.

The next three totals are negative balances printed in the same manner as the negative balance 325, the printing of which is described above.

15 The next total, a negative balance of 140, presents another condition for correction in total printing. There it is noted that the units order debit accumulator wheel remains in its normal position, keeping the sensing contacts TC closed. The totaling cams in the credit accumulator are 20 moved from their contacts 1, 2, 4, and 0 steps respectively, from the highest order down. Both the units and the tens orders now do not require correction because they have not been disturbed from the true complementary relation between 25 the upper and lower accumulator wheels. This condition is taken care of by the sensing contacts TC cooperating with the debit accumulator wheels. When the units order wheel stands in normal position, the zeroizing circuit is directed 30 over into the tens order, starting the resetting of the tens order wheel at the ten index position during the total printing of a negative balance. At such times it is noted that the units order type bar is stopped with its upper zero type in printing position. In the example given, the tens order type bar is allowed to rise 6 steps presenting a 4 type for printing. The two highest order wheels in the debit accumulator are clutched for resetting 35 at the nine index point and thus allow the type bars to partake of an extra step of movement, the hundreds order type bar rising 9 steps and presenting a 1 type for printing and the thousands order type bar rising 10 steps and presenting the lower zero for printing.

40 In the last example given on the chart, it is noted that the condition prevailing in the previous problem is carried out to another order. There it is noted that in the figure 300 taken as a negative balance, the two lower order wheels of 50 the debit accumulator are left in their normal position, thus providing for a starting of resetting of the three lower orders of the debit accumulator at the ten index position.

45 The credit accumulator totaling cams are positioned 1, 3, 0 and 0 steps, respectively, from the contacts which when closed serve to interrupt the movement of the type bar and thus present a numbered type for printing. With the negative balance of 300 to be printed under control of the 55 credit wheel totaling cams, the relation between the position of the cams and the number of steps imparted to the type bars is shown by the numerals presented in columns 5 and 6 on the last line of the chart. The two lower orders of the type 60 bars are stopped at their upper zeros when the two lower order debit wheels are zeroized at the ten index point position, energizing the printing or type bar obstructing magnets before the type bar has a chance to move. The hundreds order 65 debit accumulator wheel is also clutched at the ten point in the cycle. The totaling cam present in the credit accumulator related to this debit wheel stands 3 steps removed from its cam contacts. When rotated in the reverse direction the 70 75

wheel allows the related type bar to go through 7 steps of movement obstructing the type bar in a position to print a three. The thousands order totaling cam in the credit accumulator is positioned to normally allow 9 steps of type bar movement. However, during a negative balance total printing operation the clutching of the related debit wheel at the nine index point position allows an extra step of movement to be imparted to the 10 type bar thus allowing the thousands order type bar to rise 10 steps to present its lower zero. The amount thus printed will appear on the record strip as -300, see Fig. 11, which is the correct print of the negative balance assumed present in 15 the debit accumulator before the total printing operation was initiated.

Machine operating connections

The wiring diagram Fig. 12 shows the control 20 of the machine for effecting adding, subtracting, printing, card feeding and totaling. The control of the machine is more fully disclosed in the Peirce application, Serial No. 442,348. Only so much of the control as is necessary to understand 25 the operation of the present device is included in this diagram as the complete control wiring diagram would be so much more complicated that it would not be so readily understood without an unnecessary amount of study.

30 The source of power is at PS and includes the lines 230, 240. When a switch at PS is closed the operating motor of the machine is energized and will operate connected parts to which the various mechanisms in the machine may be clutched.

35 When the start key 260 is depressed, contacts K1, K2 will be closed. This will close a circuit from the line 230, through conductor 261, contacts K2, wire 262, card feed clutch magnet CFM, wire 263, contacts K1 now closed, wire 264, stop 40 key contacts K3 normally closed, wire 255, 256 to the line 240. The energization of magnet CFM will cause operation of the card feed mechanism to feed cards through the machine. This magnet also controls the contacts CFC1, closing them 45 when the magnet is energized. As the cards commence feeding through the machine they will depress the upper card lever UCL, closing contacts 265, 266 and opening contacts 267. The start key 260 may then be released and the circuit through 50 the magnet CFM will be maintained from line 230, through wire 261, wire 268, contacts 266, contacts 265, wire 269, wire 262, magnet CFM, wire 263, contacts CFC1, wire 264, contacts K3, wires 255, 256 to line 240.

55 Between the passage of the cards the card lever UCL is released so that contacts 265, 266 opened contacts 267 become closed. During this interval the CF1 cam permits its contacts to be closed so that the current will flow around the 60 contacts 265, 266 at this time and thus continue the circuit. While the cards are holding the contacts 265, 266 closed the CF1 contacts are held open by their cam. If cards fail to feed the 65 circuit will be broken, deenergizing the card feed clutch magnet and thus stopping the card feed mechanism.

If printing is to be effected under control of the cards being fed through the machine the switch S4 will be closed so that when the start 70 key 260 is depressed a circuit will also be established through the printing clutch magnet PCM. This circuit is as follows: from the line 230, through wire 270, printing clutch magnet PCM, through switch S4, contacts LCL1 as soon as the 75 LCL card lever is closed by the cards that are now

being fed through the machine, contacts K1, wire 264, contacts K3, wires 255, 256 to line 240.

The energization of magnet PCM causes the printing operating devices to be clutched to the main operating mechanism so that type bars 117 5 and associated mechanism are operated. After the start key is released the circuit continues through the contacts CFC1. If cards fail to feed the LCL card lever will permit its contacts to open, breaking the circuit through the magnet 10 PCM. The stoppage of the card feed mechanism by deenergization of magnet CFM also causes opening of the contacts CFC1 so that the circuit is broken at two points. When the total key is pressed to take a total, contacts TS6 will close 15 to reenergize the printer clutch magnet PCM through wire 274 so that the total may be printed.

While the machine is in operation and cards are being fed the machine may be stopped at any time by depression of the stop key 271 to open 20 the contacts K3. This will break the circuit through the card feed clutch magnet and the printing clutch magnet. The operating motor will, of course, continue to operate until the switch at PS is opened.

A platen feed mechanism is provided to feed the record paper before printing in both listing and total operations. A platen feed magnet PFM, when energized acts to clutch the platen spacer to the driving mechanism. The circuit through 30 the platen feed magnet is as follows: line 230, magnet PFM, wire 272, contacts PM3 closed before printing, magnet PFM, wire 273 and wire 246 to the other line 240.

A number of circuit closing contacts shown in 35 Fig. 12 are operated by certain parts of the machine depending upon whether the contacts are to be operated during a card feeding cycle or during a totaling cycle of the machine when feeding is not being effected. The contacts and cams 40 that are operated during the card feeding cycle of the machine when the machine is either adding or subtracting, during which operation listing of the amounts added and subtracted may also be effected, are designated CF cams and contacts. 45 All of the CF cams may be mounted on the shaft 275 of Fig. 1 which shaft is operated when cards are being fed through the machine.

Other cams and contacts are designated as CR 50 cams and contacts. These cams are continuously operating whether the machine is adding and subtracting or totaling. These cams may be mounted for operation on shaft 10 (Fig. 2) which shaft is always turning. Certain contacts not operated by cams and designated TS contacts may 55 be normally opened or normally closed and are controlled by plates 101, Figs. 2 and 6.

When the machine goes into a totaling operation, magnet TSM is energized to shift the parts so that the open TS contacts become closed and 60 those that are closed become opened. The contacts designated SB are adapted to be opened or closed when the subtraction magnet SBM is energized. The contacts designated MB are adapted to be effected when the minus balance 65 magnet MBM is energized.

Accumulating and listing

When cards are fed through the machine they 70 first pass under the upper brushes 276 at UB (Fig. 12) and then under the lower brushes 90 at LB. While a card is under the brushes 90 the contacts CF3 are closed by their cam. If a perforation appears in any column on the card, when such perforation passes under a brush 90 75

a circuit will be set up through the perforation as follows if the card is a credit card: from line 230, through the LCL2 contacts which are held closed by the cards while cards are feeding, through contacts CF3 and through the brush 271 to the common contact roller 278, then through the perforation in the card to the brush 90, to plug socket J1, through a plugging wire to the socket J3, to contacts 278 closed mechanically on every card feeding cycle, through cable 280, through contacts SBF, wire 281, through magnet 25, to bus bar 238, and through wire 239 to the other side of the line 240.

The energization of magnet 25 as we have seen in connection with Figs. 4 and 5 causes the accumulator gear 46 to commence to turn in accumulating. It commences to turn at a point in the cycle when a perforation passes under the brush 90, and ceases to rotate when the cam point 41 (Fig. 3) causes the pinion 35 to become disengaged from gear 36. Thus the amount represented by the position of the perforation is added in the upper credit wheel and, through gearing 47, 50, subtracted from the lower debit wheel.

The circuit through the brush 90 also effects printing through the following circuit: from the plug socket J3 through contacts TSA closed during listing, wire 282, through printing magnet 108, to bus bar 248 and through wire 249 to the other side of the line 240. The energization of printing magnet 108 as described in connection with Fig. 2 controls the setting of the type carrier 117 to cause printing of the character represented by the position of the hole in the card.

Carrying from one order on an accumulator to the next higher order is effected as follows: if the credit accumulator wheel of any order passes from nine to zero during an adding operation it will cause the brush 65 to rock into position to be later engaged by the segment 68 on commutator 69 as has been described. After the accumulator wheel has been disengaged, the contacts CF2 are closed momentarily. This closure takes place at the moment when the commutator segment is passing the position of brush 65. If the brush has been rocked so as to be engaged by the segment, a circuit will be closed at this moment from the line 230, through wire 283, contacts CF2, contacts SBA closed during credit item entering, bus bar 284, brush 65, commutator 69, brush 75, wire 285, magnet 25 of the next higher order, bus bar 238, and through wire 239 to the other side of the line 240. As soon as a single step of carrying movement has been rolled into the wheel, the cam point 415 (Fig. 3) will cam the pinion 35 out again so that the accumulator wheel again stops after having received an additional unit. If any accumulator wheel is standing at nine when an additional unit is added to it, we have seen that its brush 78 (Figs. 5 and 12) will be in position to be engaged by segment 79 on commutator 69. This engagement also takes place during the moment that contacts CF2 are closed.

Thus when current passes from the brush 75 to wire 285 it will also pass on to brush 78, through commutator 69 of the next higher order, then to brush 75 of that order and out to the next wire 286 and on to the adding magnet 25 of the order above to cause a unit to be added to such order. Thus if the accumulator wheel of the tens order is standing at nine at the end of an accumulating operation and the wheel of the units order passes from nine to zero, a unit will be carried into the accumulator wheel of the tens

order and through the brush 78 of the tens order into the accumulator wheel of the hundreds order, and so on.

If the card carries a debit amount, one of its columns will be perforated with a hole in a position above the amount perforation positions. The brush 287 in the upper brushes (Fig. 12) which reads this particular column is connected by the plug line 288 to the subtraction magnet SBM which serves to set the devices so that the number on the card is added on the lower or debit accumulator shown in Fig. 3. Thus if there is a perforation in this position, brush 287 will make contact with the common contact roller 289 and set up a circuit from the line 230, through wires 261, 268, contacts 266 now closed, wire 290, contacts CF5 closed while the brushes are passing the extra perforation, subtracting magnet SBM, plug J6, plug wire 288, brush 287, contact roller 289, brush 291, wire 292 and back to the line 240. The energization of magnet SBM serves to open the contacts SBA, SBF, and close the contacts SBB, SBE. These contacts will remain in their changed position while the card is passing under the lower brushes 90 and then be restored mechanically as shown in Fig. 9 of Patent No. 1,914,285. The changed relation of the SB contacts directs the accumulating and carrying impulses through the lower or debit accumulator and opens the circuits through the upper or credit accumulator which is then driven in a reverse direction by gearing 47, 50 as explained hereinbefore.

When the debit card is passing under the lower brushes, the amount readings sensed by brushes 90 will be transmitted the same as credit amounts through plug socket J3 and through cable 280, but since contacts SBF are opened and contacts SBE are closed by magnet SBM, the impulses will be directed through magnets 40, through bus bar 238 and wire 239 to the other side of the line 240. The carry circuit is changed so that the circuit is closed through the brushes 65 in the debit accumulator by closing contacts SBB, and the credit accumulator brushes are disabled electrically by breaking the circuit through the upper contacts SBA. If the units wheel in the debit accumulator passes from nine to zero, brush 65 will contact commutator 69 and a circuit will be established from line 230, wire 283, contacts CF2, contacts SBB, bus bar 238, brush 65, commutator 69, brush 75, wire 294, magnet 40 in the tens order, bus bar 238, and wire 239 to the other side of the line 240. If the tens order wheel should have been standing at nine, brush 78 would be contacting commutator 69 and a circuit would be established through wire 295 to the magnet 40 in the hundreds order. The printing of the debit amount is performed by energization of magnet 108 by impulses transmitted over the same circuits used in listing credit amounts.

Totaling operation

To take a total, the total key 296 is depressed closing contacts K4, Fig. 12. This energizes magnet TSM as soon as the CR1 contacts are closed. The circuit is from line 230, through wire 261, wire 268, contacts 267, contacts K4, magnet TSM, contacts CR1, wire 297, wires 254, 255, 256, to the other side of the line 240.

The contact blades 99 and 100 are then shifted by the mechanism shown in Fig. 6. The other TS contact blades will also be shifted.

As explained hereinbefore, if the amount standing in the accumulators is a minus balance, the credit accumulator wheels will contain a

complement and the debit accumulator will contain a true number as a balance. The accumulator wheel of the highest order in the credit accumulator will contain a nine and the corresponding debit wheel will stand at zero. Whenever a total is to be taken, the wheel 213 of the highest order in the debit accumulator is analyzed for a zero. If it contains a zero, devices are set up to print the total by zeroizing or clearing the debit accumulator instead of the credit accumulator. After the total key 296 has been depressed and the contacts TS1 closed, current will pass from line 230 through wire 250, contacts CR6 now closed, wire 251, contacts TS1, 15 magnet MBM, contacts B1, and wire 253 to line 240. This magnet MBM opens contacts MBE, MB5C and closes contacts MBD, MB6, and MB5D. The closing of contact MB5D serves to direct a circuit through magnet 2CM instead of 20 magnet 1CM. The action of these magnets in cooperation with the mechanism in Figs. 7 and 8 in governing the timed closing of the zeroizing contacts 1CC and 2CC is described hereinbefore in connection with Figs. 7 and 8. The circuit 25 including magnets 1CC and 2CC is arranged from line 230, through wire 310, contacts CR7, contacts TS2, through blade 435 and either contact MB5C or MB5D, through either magnet 1CM or magnet 2CM, and wire 246 to the line 30 240.

The closing of contacts MB6 by the minus balance magnet when a negative balance appears in the accumulators, serves to bring a zeroizing impulse at the ten index point position directly to the lower orders of the debit accumulator. The impulse is directed into the units order debit bank and connections are made across the debit accumulator through the TC contacts so that any number of lower order banks 35 in series may be conditioned for zeroizing at the ten index point position if the wheels are positioned in the normal position. The circuit is from line 230, contacts TS5, contacts CR2, CR3 closed at 40, wire 311, contacts MB6, wire 312, contacts TSD now closed, contacts MBD, and 40 through the units order debit accumulator magnet 40, bar 238, wire 239 to line 240. The circuit continues across the accumulator through wire 313 connected to wire 312, contacts TC associated with the units order debit wheel, wire 314, 45 through the tens order debit accumulator magnet 40. A wire 315 and units order contacts TC connect wire 313 with the tens order contacts TC and so the connections are made across 50 the debit accumulator to wire the magnets 40 in multiple with the zeroizing circuit through the contacts TC.

The closing of contacts MBD acts to direct the zeroizing impulses through magnets 40 instead 55 of magnet 25 when a total is being taken with a negative balance in the accumulator.

Assuming now that a positive balance is present in the accumulator when a total is taken, the minus balance magnet will not be energized. 60 The magnet 1CM will be energized to close the zeroizing contacts 1CC at the ten index point position in the cycle, and the contacts MBE will remain closed to direct the zeroizing impulses 65 through the credit accumulator magnets 25.

70 The zeroizing circuit is then from line 230, contacts TS5, contacts CR2 and CR3, bar 316, contacts 1CC, wire 317, wire 318, wire 314 (wire 312 in the units order) contacts TSD, contacts MBE, wires 236, magnets 25, bar 238, wire 239 and line 240. The credit accumulator wheels 75

are then all thrown into mesh for operation and will be conditioned to turn through ten steps, and each wheel will turn additively until interrupted. While the credit accumulator wheels are turning, a circuit is prepared for total printing by the energization of printer magnets 108. The circuit is as follows: line 230, contacts TS5, contacts CR2 and CR3, bar 316, contacts 1CC, wire 317, to upper contact TC. The cams 213 are turning with the accumulator wheels. When a raised portion on cam 213 closes contact TC the printing circuit will continue through cable 245, contacts TSC closed during totaling, wire 282, magnet 108, bar 248, wire 249 and line 240. The energization of magnets 108 will set 15 the respective type bars for printing the total of the positive balance which was standing on the credit accumulator wheels. The accumulator wheels will be demeshed at the zero position, the grooved bar 184 of Figs. 3 and 4 having released the levers 198 to permit the frames carrying the pinions 35 to be cammed and latched out so that the accumulators will be cleared and ready for a new accumulating operation. 20

When a negative balance is stored in the accumulator and the total key is depressed, the minus balance magnet circuit will be energized as a result of testing the standing of the highest order debit wheel which then is at zero. Contact MB5D controlled by magnet MBM is closed and 25 a circuit is established through magnet 2CM which serves, in cooperation with the mechanism in Figs. 7 and 8 as explained hereinbefore, to cause the delayed closing of the contacts 2CC. 30

The contacts MB6 are closed and at the ten 35 index position a zeroizing impulse is sent through contacts TS5, contacts CR2 and CR3, wire 311, contacts MB6, wire 312, contacts TSD, contacts MBD, wire 237, magnet 40, bar 238, wire 239 and line 240. This initial zeroizing impulse is adapted 40 to be directed across the accumulator by wires 313, 315, etc., according to the number of lower order debit wheels in normal position with contacts TC closed. The contacts MBD are closed for negative totals so that the zeroizing impulses through the 45 contacts 2CC are directed through the debit accumulator magnets 40. The circuit is from line 230, contacts TS5, contacts CR2 and CR3, bar 316, contacts 2CC, wire 317, wire 318, wire 314, contacts TSD, contacts MBD, wire 237, magnet 40, bar 238 50 and wire 239 to line 240. The debit accumulator wheels are then meshed with the actuating gears; one or more of the lower order wheels meshing at the ten index position and all the higher order wheels meshing at nine index position. Through 55 the gear connections 47, 50 the credit wheels are rotated in the reverse of the normal movement by the debit wheel clearing movement. The cams 214 on the credit wheels will approach the levers 215 in the opposite to the usual direction of movement 60 to close the total printing control contacts TC. The debit wheels rotate until they reach the normal position at which time they are demeshed in position for a new accumulating operation. The circuit through the upper contacts TC during the 65 registration of a negative balance is as follows: line 230, contacts TS5, contacts CR2 and CR3, bar 316, contacts 2CC, wire 317, contacts TC closed differentially, cable 245, contacts TSC, wire 282, magnet 108, bar 248, and wire 249 to the line 240. 70 The typebars are then stopped to print the negative balance in the manner explained hereinbefore with reference to Fig. 10.

Since the basic novel features of the invention have been shown and described as applied to a 75

single modification, it will be understood that various omissions and substitutions and changes in the form and details of the device illustrated and changes in its operation may be made by those skilled in the art without departing from the spirit of the invention. It is the intention, therefore, to be limited only as indicated by the scope of the following claims:

1. In an accumulating device, a plurality of accumulating elements, means for actuating said elements, means for engaging said elements with the actuating means, and means under control of one element of the device for changing the instant at which said engaging means operates to engage 10 the next higher order element with the actuating means.
2. In an accumulating device, an accumulating element, a next higher order accumulating element, means for actuating said elements, means 20 for engaging said elements with the actuating means, and means controlled by the position of said first named element for varying the instant of engagement of the next higher order element with the actuating means.
3. In an accumulating device, an accumulating wheel, means for actuating said wheel, means for engaging said wheel with the actuating means, electrical control devices for governing the operation of said engaging means and the instant of 30 initial engagement of said accumulator wheel with said actuating means, said devices including means for sensing the position of another wheel in said accumulator and for controlling the governing operation of said devices according to the 35 position of said another wheel.
4. In an accumulating device, a constantly running driving member, a type carrier adapted to be moved in synchronism with said driving member, a pair of accumulating elements, means for engaging either of said elements to said driving member for zeroizing during total taking, means for changing the instant of engagement of one of said elements during total taking, and means under control of said elements for stopping said 45 type carrier differentially.
5. In an accounting machine of the class described, a pair of accumulators for accumulating positive and negative amounts, electrically controlled means for entering an amount in either 50 of said accumulators, connections between said accumulators so arranged that an amount added in one accumulator will be subtracted from the other accumulator, means for selecting and operating either accumulator in total taking and simultaneously driving the other accumulator through 55 said connections, and printing means having connections to only one of said accumulators to control the printing of positive and negative balances.
6. In an accounting machine of the class described, a credit accumulator, a debit accumulator, means for adding credit amounts in the credit accumulator, means for adding debit amounts in the debit accumulator, connections between related orders of the accumulators so arranged that an 60 amount added to the number standing on one accumulator will be subtracted from another number on the other accumulator, said another number being the complement of said first mentioned number, means for sensing the presence of a 65 balance on one of said accumulators, means under control of said sensing means for determining the amount of the balance standing on one of the accumulators by reading the wheels of the other accumulator, and means under control of the last 70 mentioned means for printing the balance.
- 75

7. In a machine of the class described, a pair of accumulators, means for printing totals accumulated by said accumulators, a total reading circuit associated with one of said accumulators, contacts in said circuit closed by said accumulator to determine the amount printed, and means including said one accumulator for operating said contacts under the control of the other accumulator. 5

8. In an accumulating mechanism, an accumulator wheel, means for rotating said wheel, printing means, an electric circuit for controlling said printing means, contacts for closing said circuit, a cam attached to said wheel, a cam lever in cooperation with said cam, and operated by the 15 cam as the wheel assumes its zero position, serving to operate the contacts and close said circuit, another accumulator wheel having connections to the first mentioned wheel and adapted to reverse the movement of said wheel to vary the time 20 of closing said contacts.

9. In an accumulating device, a plurality of accumulating wheels, means for printing a total under control of said wheels, means for restoring said wheels during total printing, means for engaging the lower order accumulator wheel with said restoring means early in the total printing operation, means for conditioning any wheel above a lower order wheel standing in its normal position, for engagement with the restoring 30 means early in the total printing operation, and means for engaging all higher order wheels with said restoring means after an interval of time of operation of said restoring means during total printing. 35

10. In a machine of the class described, a pair of accumulators, means for actuating said accumulators, type carriers adjusted under control of said accumulators and movable in synchronism with said accumulator actuating means, means for determining which accumulator holds a total as a positive number, zeroizing devices for governing the time of engagement of said accumulators with said actuating means, means under control of said determining means for selecting the zeroizing device to be operated, means whereby one of said zeroizing devices acts to engage one of said accumulators with its actuators in the initial portion of movement of said type carrier, and means under control of the other of said zeroizing devices for engaging the other accumulator with its actuating means after one step of movement of said type carriers. 50

11. In a perforated record controlled machine, means for analyzing the records placed in the machine, a credit accumulator with its wheels normally at zero, a debit accumulator with its wheels normally at nine, item entering means under control of said analyzing means for adding credit items to the credit accumulator and debit items to the debit accumulator, gear connections between the accumulators enabling either accumulator when adding an item to the number standing on its wheels to rotate the other accumulator in a reverse direction subtracting the item from the number standing on the other accumulator wheels, means cooperating with the highest order wheel in the debit accumulator to detect the presence of a zero on that wheel, and means under control of said detecting means, for printing a debit balance under control of the credit accumulator wheels if the highest order wheel stands at zero, or printing a credit balance under control of the credit accumulator wheels. 65 70

if the highest order debit wheel does not stand at zero.

12. In a machine controlled by records perforated to represent positive and negative amounts, means for sensing said perforations, a pair of accumulators for accumulating positive and negative amounts, means under control of said sensing means for operating said accumulators, and means for taking a reading of the balance amount in either of said accumulators from one of said accumulators.

13. In a machine controlled by records perforated to represent positive and negative amounts, means for sensing said perforations, a pair of accumulators for accumulating positive and negative amounts, means under control of said sensing means for selectively operating either of said accumulators, connections between said accumulators so constructed that an amount added in one accumulator will be subtracted from the other accumulator, means for selecting and operating either accumulator in total taking and simultaneously driving the other accumulator

through said connections, and printing devices controlled by one of said accumulators to print positive and negative balances.

14. In an accumulating device, an accumulator wheel standing at zero, electrical devices under control of said wheel for printing either "0" or "9", an adjacent accumulator wheel, and contacts operated under control of said adjacent wheel for controlling said printing means to select the printing of "9".

15. In an accumulating device, an accumulator wheel registering zero, a type carrier, electrical devices under control of said wheel for positioning said carrier to print "0", electrical controls for changing the operation of said positioning means to put said carrier in a position to print "9", an adjacent accumulator wheel, and contacts connected to said controls and operated under control of said adjacent wheel for rendering said changing means operative when said adjacent wheel registers a significant digit.
